Primary Examiner — Joseph Kukella*Assistant Examiner* — Molly Loch(74) *Attorney, Agent, or Firm* — Leason Ellis LLP(57) **CLAIM**

The ornamental design for a doorbell, as shown and described.

DESCRIPTION

FIG. 1 is a top, front, right side perspective view of a doorbell showing our new design;

FIG. 2 is a top, back, left side perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines in the drawing figures are for the purpose of illustrating portions of the doorbell that form no part of the claimed design.
